4 Claims. (Cl. 242—56)

The present invention relates to winding method and apparatus for winding web, particularly to provide an improved winding method and apparatus for winding web having constant length.

In the conventional method of winding web, such as fabric, paper, synthetic film, etc., the fully wound web is taken off from a supporting member and an empty mandrel is inserted into the supporting member. After winding web having a desired length the supplied web is cut and the forward edge portion of the supplied web is instantly fixed on an empty mandrel by means of using bonding agent or a suitable catch member, and these operations have usually been performed manually. However, these manual operations have prevented an increase in efficiency of winding web and have been considered troublesome, because they require stopping the winding operation while they are performed.

The principal object of the present invention is to provide a winding method and apparatus for winding a constant length of web around succeeding mandrels continuously, without any manual operation and stopping of the winding operation.

The other object of the present invention is to provide winding apparatus for winding web having a constant length around succeeding mandrels, comprising an automatic cutting means for the supplied web when the length of wound web is as desired, an automatic attaching means for attaching the forward edge portion of the supplied web to an empty mandrel, an automatic changing means for changing a fully wound mandrel for a succeeding empty mandrel.

According to the present invention, all operations, such as, the operation of cutting the supplied web when the length of wound web around the mandrel is as desired, the operation of fixing the forward end portion of the supplied web, and the operation of changing from a fully wound mandrel to a succeeding empty mandrel, are performed automatically without any stopping of feeding and winding web around a mandrel, whereby the so-called machine-efficiency can be increased, and moreover, winding speed can be increased. By attaching the forward end portion of the supplied web onto the empty mandrel automatically by means of applying fixing means according to the invention, uniform effect of attaching also can be provided, whereby any occurrence of crease on the wound web can be provided.

Further features and advantages of the invention will be apparent from the ensuing description with reference to the accompanying drawings to the scope of the invention is in no way limited.

FIG. 1 is a side view, particularly shown fixing means in section, of the winding apparatus according to the present invention.

FIG. 2 is a fragmentary front view of cutting means of the present invention.

FIG. 3 is a sectional view of cutting means taken along line III—III of the drawing of FIG. 2.

FIG. 4 is a side view, partly in section of the actuating member of fixing means shown in FIG. 1.

FIG. 5 is a sectional view of the holder of the fixing means taken along line V—V of the drawing shown in FIG. 1.

2

FIG. 6 is a fragmentary side view of the stopper engaging with the fixing means shown in FIG. 1.

FIG. 7 is a fragmental side front view of the stopper engaging with the fixing means seen from line VII—VII of the drawing of FIG. 6.

FIG. 8 is a fragmentary front view of winding means, including cutting means, according to the invention.

FIG. 9 is a fragmentary front view showing a gear arrangement of turret mechanism of winding means of the invention.

An embodiment of winding apparatus according to the present invention is shown in FIGS. 1, 2, 3, 4, 5, 6 and 7. A feeding web 1 is passing upon an empty mandrel M1 and winding around a mandrel M2. The mandrels M1 and M2 are rotatably supported by a pair of supporting arms 2, respectively. A fixing means and a cutting means are disposed above the winding means as shown in FIG. 1. A traverse member 3 slidably engages with the traverse guide 4 which is rigidly supported by frame F. A pair of shafts 5 and 6 are disposed at the lower extended portion 7 of the traverse member 3. A pinion 9 and toothed wheel 10 are secured to the shaft 5, and a toothed wheel 12 and cutting wheel 11 are secured to the shaft 6 respectively as shown in FIGS. 2 and 3. The toothed wheel 10 meshes with the toothed wheel 12, and the pinion 9 meshes with a rack 13 which is disposed under the traverse guide 4 as one body. The traverse member 3 is connected with chain 14 at its upper portion. The chain 14 traverses according to the actuating motion of actuating member (not shown) when the length of wound web around the mandrel becomes desired one, therefore, the traverse member 3 traverses along the traverse guide rod 4. By this traverse motion of the traverse member 3, the pinion 9 is rotated by gearing with the rack 13, the cutting wheel 11 is rotated by rotation of the shaft 6 on which toothed wheel 12 is secured so as to mesh with the toothed wheel 10 which is secured on the shaft 5. As mentioned above, during the transverse shifting motion of the traverse member 3, the cutting wheel 12 is cutting the supplied web by its rotation, and after the respective transverse shifting and cutting motion of the traverse member 3 and the cutting wheel 12, the traverse member 3 returns to its original position according to return motion of the chain 14. A guide plate 15 is disposed at the end of the elongated portion of the traverse member 3 at a right angle to the extended portion of the traverse member 3. The guide plate 15 works as so-called chopping board when the cutting roll 11 works to cut the supplied web 1. In FIGS. 1, 4, 5, 6 and 7 a punching tack holder 16 is secured to a shaft 17, and punching portion 18 is disposed at the forward end portion of the tack holder 16 so as to face to the empty mandrel M1. Tack assembly 19 has a U section with sharp edges and is inserted into the tack holder 16 so as to be able to be slid along a guide bar 20 by pushing member 21 which is actuated by a spring 22, when one tack of the tack assembly 19 is pushed out of the tack holder 16. A plunger holder 23 is secured to a supporting member 24 at the corresponding portion upon the punching portion 18. A plunger 25 is disposed vertically in the plunger holder 23, and the bottom end of the lower elongated portion 26 of the plunger 25 approaches the punching portion 18, and a spring 27 for return motion of the plunger 25 to upward direction is disposed inside the plunger holder 23 as shown in FIG. 1. A set screw 28 works to set the supporting member 24 to the punching tack holder 16. A lever 29 is pivoted to a shaft 17 and one end of the lever 29 forms an impact head 30 for striking head 31 of the plunger 25 and the other end is articulated to a piston rod 33 of fluid pressure cylinder 32. Both end portions of the fluid pressure cylinder 32 are connected with a transfer valve

34 which transfers the connection of fluid conduit with the other end portions of the fluid cylinder 34 by an action of suitable actuating member, such as magnetic clutch, when the winding length of web around the mandrel becomes desired length.

As shown in FIGS. 4 and 5, a fulcrum portion of the lever 29 is secured to the shaft 17 by key, and an end portion of the tack holder 16 is connected by pin 35 to fulcrum cylindrical portion of the lever 29, and a groove 36 extending 0° angle around the axis of fulcrum portion of the holder 16 is disposed at the corresponding position of pin 35 as shown in the drawings. A control roll 37 is disposed at almost middle portion of the lower extended portion 7 of the traverse member 3.

By the above-mentioned punching tack members, when the length of wound web around the mandrel M2 becomes desired length, a suitable detecting member (not shown) detects the wound length and actuates the transfer valve 34 so as to pull the piston 33 upward direction, then the lever 29 rotates in a clockwise direction, however, the control roll 37 prevents downward movement of the impact head 30 past the control roll 30. After transverse movement of the traverse member 3, that is, after the impact head 30 leaves the roll 37, the piston 33 further moves in an upward direction by the pulling action of the fluid cylinder 32 and the impact head 30 is pushed downward, while the tack holder 16 is also rotated in a clockwise direction around the pivot shaft 17. When the bottom portion of the tack holder 16 contacts the empty mandrel M1, through the supplied web, the holder stops its rotational movement, however, the impact head 30 of the lever 29 still rotates in a clockwise direction, because of the existence of the groove 36 which permits excess angular movement 0° around the pivot shaft 17. Therefore, the impact head 30 strikes the head 31 of the plunger 25 so as to strike and push out the end tack of the tack assembly 19 from the tack holder 16, and the tack is pushed into the mandrel M1. According to the width of supplied web, plural tack holders can be arranged along the supporting shaft 38 so as to insert punching tacks into the empty mandrel M1 at transversely displaced positions along the shaft 38. By the above-mentioned punching tack operation, the forward end portion of supplied web can be rigidly attached to the empty mandrel M1, while the above-mentioned cutting roll 11 is operating.

After the punching operation, the control valve 34 actuates to change the fluid pressure of the cylinder 32 so as to push out the piston 33, that is, the lever 29 and the tack holder 16 return to the original position so as not to interfere with the return motion of the cutting roll 11.

In an embodiment of winding means of the present invention plural winding mandrels are supported by supporting member and provided with rotation by driving means, and can be changed from their disposed position relatively at any desired time automatically. Therefore, winding efficiency can be improved. It is one of the functional features of the winding means of the invention, which is clearly shown according to the following description. In FIG. 8, a central shaft 39 is supported by a pair of frames 40, a pair of supporting arms 41 are supported symmetrically by the central shaft 39. Supporting arms 41 are provided with supporting portions 42, 43 and 44, 45 respectively, at both end portions of the respective arms 41 symmetrical to the central shaft 39. Rotatable shafts 46 and 47 are supporting by the supporting portions 42, 44 and 43, 45 respectively. Mandrels M1, M2 are supported by the shafts 46, 47 so as to rotate together with the respective shaft. Sprocket wheels 48 and 49 are secured to the shafts 46, 47 respectively and a sprocket wheel 50 is loosely secured to the shaft 39. The sprocket wheel 50 is driven by a main sprocket wheel (not shown) and the sprocket wheels 48 and 49 are driven by the sprocket wheel 50 through chaindrive means 51

and 52, respectively, as shown in the drawing of FIG. 8. After winding the forward end portion of the supplied web after aforesaid punching operation and after winding length of supplied web around the mandrel M1, the pair of supporting arms 41 are subjected to rotate 180° by suitable turning mechanism, such as turret mechanism as shown in FIG. 9. In FIG. 9 a turret plate 53 is rotatably secured to the central shaft 39 and the driving shafts 46 and 47 are supported at the symmetrical position of the turret plate 53 to the central shaft 39. The turret plate 53 is provided with worm wheel 54 as shown in the drawing and the worm wheel 54 meshes with worm 55 which is driven by the driving motor 56 through ideal gearing 57. When the actuating means actuates the driving motor 56, the turret plate turns 53 180°, according to the rotation of the driving motor 56.

After the 180° turning motion, the position of the mandrels M1 and M2 are reversely changed, and the supplied web 1 is wound around the mandrel M1, while the mandrel M2 works as guide roller.

When the length of winding web around the mandrel M1 becomes of desired length, a driving shaft 57 is driven by an actuating member (not shown) and rotated to clockwise direction as shown in the drawing of FIG. 8. 25 A sprocket wheel 58 is rigidly secured to the shaft 60 and an endless chain driving means 14 passing guide sprocket wheels 59 disposed on the frame are driven by the sprocket wheel 58 so as to rotate the direction of arrows 62 in the drawing. As described above, the chain 30 14 is secured to the top portion of the traverse member 3 so as to drive along the traverse guide 4. By this transverse movement of the traverse member 3, the cutter roll cuts 11 the supplied web along the traverse guide 4 as described above. After starting this cutting operation, 35 above-mentioned punching tack operation is provided so as to fix the forward end portion of the supplied web on the empty mandrel by tack, and after this punching operation and its return operation, the driving shaft 60 turns to the opposite direction so as to return the traverse 40 member 3 to its original position. And after the length of wound web becomes some length, the position of mandrels are changed reversely as mentioned above, and when the length of wound web around the mandrel becomes to desired one, the cutting operation of web is actuated by 45 suitable actuating means (not shown), and the above-mentioned successive operations are repeated.

In the above-mentioned operation, the timing of starting each operation should be designed according to machine speed.

As described above, all operations are performed automatically, the winding efficiency and quality of winding can be improved remarkably according to the method of and apparatus winding web of the present invention.

While the invention has been described in conjunction 55 with certain embodiments thereof is to be understood that various modification and changes may be made without departing from the spirit and scope of the invention.

What I claim is:

1. Apparatus for winding web, comprising a plurality 60 of mandrels, means for rotationally driving said mandrels, means supporting one of the mandrels in a position to guide the web and another of the mandrels in a position to wind the web from the guide mandrel, means for cutting the web when a desired length thereof has been 65 wound on the mandrel in the winding position, means for fixing the forward end of the cut web onto the mandrel in the guiding position, and means for reversing the positions of the mandrels after the forward end of the cut web has been fixed onto the mandrel in the guiding 70 position.

2. Apparatus according to claim 1, in which said fixing means comprises a tack holder having an end disposed above the mandrel in the guiding position, a plunger holder disposed above said end of said tack holder, means 75 to control operation of said tack holder and said plunger

holder, a lever one end of which is connected to said control means, said lever at its middle portion being pivotally mounted on said shaft and articulated at the point of said pivotal mounting, one end of said lever defining an impact head and the other end of said lever being connected to said control means, said tack holder and said plunger holder being mounted on said lever, a plunger slidably mounted in said plunger holder, a spring mounted in said plunger holder to urge said plunger in an upward direction, the lower end of the plunger extending below the plunger holder to a position immediately above a tack positioned at said end of said tack holder, the upper end of the plunger extending above the plunger holder and being disposed immediately below said impact head of said lever, said control means including means to pull the end of the lever to which it is attached upwards thereby to cause the plunger holder and the tack holder to move downwards until the tack holder abuts against the mandrel in the guiding position and said lever at the point at which it is articulated and pivotally mounted on said shaft being provided with means to permit said impact head to continue moving downwards when said tack holder has abutted against the mandrel in the guiding position whereby the impact head strikes the upper end of the plunger causing the lower end of the plunger to strike the tack and drive the tack into the mandrel.

3. Apparatus according to claim 2, in which said cutting means comprises a transverse guide disposed above the mandrels and extending parallel to the axes of rota-

tion of the mandrels, a rack defined along the length of said guide, a carrier slidably mounted on said guide, a first shaft mounted on said guide and carrying at one end a pinion in engagement with the rack and at the other end a gear wheel, said carrier having a downwardly extending arm through which are mounted two shafts, one above the other and both below the aforementioned shaft, mounted on the upper of said two shafts a pinion in engagement with the gear wheel mounted on the uppermost shaft and a gear wheel, mounted on the lower of said two shafts a cutter wheel extending below the bottom of the arm and a pinion in engagement with the gear wheel mounted on the upper of said two shafts, means to drive said carrier along said guide thereby to cut the web and then to return the carrier back along said guide to its original position.

4. Apparatus according to claim 3, in which said arm is provided at its lower end with a plate-like extension in a horizontal plane immediately below the cutter wheel, said plate-like extension being adapted for passage of the web between it and the cutter wheel, whereby the plate-like extension provides a bearing surface for the web while the web is being cut.
